UNITED STATES PATENT OFFICE

GEORGE W. HOLCOMB, OF EAST ROCHESTER, NEW YORK

DUPLEX WATCH SUPPORT

Application filed October 26, 1929. Serial No. 402,769.

The object of this invention is to provide a new and improved double or duplex hook or support for watches.

Another object of the invention is to provide a double hook made from one piece of wire, one end thereof being adapted to support big or small watches from the ring thereof and the other end being adapted to support wrist watches from the strap thereof.

10 Another object of the invention is to provide a hook that can be fastened to a board by means of a screw, the hook being provided with an eye to receive the screw.

15 These and other objects of the invention will be illustrated in the drawings, described in the specifications and pointed out in the claims at the end thereof.

In the drawings, Figure 1 is a front elevation of the hook.

20 Figure 2 is a side elevation of the hook.

Figure 3 is a top plan view of the hook.

Figure 4 is a rear elevation of the hook.

25 Figure 5 is a front elevation of a board on which several of these double hooks are mounted showing several ways in which they are used for supporting watches.

Figure 6 is a side elevation of a special form of screw that would be used for fastening the hook on the board.

30 In the drawings like reference numerals indicate like parts.

The double hook in question is made from a wire blank of suitable length. At an intermediate part thereof, an eye 1 is coiled

35 up therein that is adapted to be engaged by a screw 2 which is screwed into the board 3 and clamps the eye 1 between the board 3 and the head of the screw. The blank wire that is left on one end of the eye is bent in the form of a hook 4 and the blank wire that is left on the other end of the eye is formed into an arm 5 of which the outer end is turned up into a small hook 6. The hook 4 is formed so that it stands at right angles to the arm 5.

40 When the hook is fastened to the board, the screw is first put through the eye in the direction shown in Figure 2, namely, so that the head of the screw is adjacent to the arm 5 and the point of the screw comes out at the

45 end of the eye where the hook 4 begins. When

the hook is fastened against the board in this way, the vertical member 7 of the hook 4 will rest against the board and the hook 4 will extend out and up from the lower end thereof. The hook 4 is adapted to hold the watch by the ring thereof and the upper outer end of the hook 4 comes close enough to the head of the screw so that there is little or no danger of the watch being accidentally knocked off the hook.

55 The horizontal arm 5 is spaced out from the board 3 so that there is clearance between it and the board. This arm is adapted to receive the strap of a wrist watch. The upturned end 6 is adapted to keep the strap 60 from sliding off the arm. In this way the one double hook can serve either of two purposes.

65 Ordinarily a round headed screw with a slot in the head will be used to fasten the hook 70 on the board, but a screw having a round head with a slot in front and having a short taper on the back of the head ending with a flat bearing surface as shown in Figure 6 will 75 also be used. The flat surface will be sufficient to make contact with the end of the eye of the hook without spreading it.

75 It will also be understood that the hook 4 can be bent so that it will normally engage 80 in the slot in the head of the screw as shown in Figure 3. This will further prevent a watch from falling off of the hook in the handling of the board or tray to which the hook is fastened.

85 It will also be understood that the hook will hold the watch against the board so that there will be no tendency for it to swing.

I claim:

90 1. A double hook for hanging watches formed of a single blank of wire, a tubular eye formed therein intermediate the ends thereof, a V shaped hook formed at one end of the eye extending out along the axis of the eye, an arm extending laterally from the other end of the eye, said hook being 95 adapted to be fastened to a board by a screw passing through the eye, the hook being held thereby with the back part of the V shaped hook against the board and being adapted to hold a paper between it and the board. 100

2. A double hook for hanging watches formed of a single blank of wire, a tubular eye formed therein intermediate the ends thereof, a V shaped hook formed at one end 5 of the eye extending out along the axis of the eye, an arm extending laterally from the other end of the eye, said hook being adapted to be fastened to a board by a screw passing through the eye, the outer end of the V normally standing close to the head of the screw.

10 3. A double hook for hanging watches formed of a single blank of wire, a tubular eye formed therein intermediate the ends thereof, a V shaped hook formed at one 15 end of the eye extending out along the axis of the eye, an arm extending laterally from the other end of the eye, a screw for fastening said hook to the board, said screw having a head thereon having a short taper on the 20 back of the head ending with a flat bearing surface adapted to make contact with the end of the eye of the hook.

In testimony whereof I affix my signature.
GEORGE W. HOLCOMB.
